UNITED STATES PATENT OFFICE.

JOHN H. LANGE, OF NEW YORK, N. Y., ASSIGNOR TO WARREN, LANGE & CO.,
OF SAME PLACE.

DESIGN FOR PAPER-HANGINGS.

SPECIFICATION forming part of Design No. 20,194, dated October 7, 1890.

Application filed September 9, 1890. Serial No. 384,467. Term of patent 3½ years.

To all whom it may concern:

Be it known that I, JOHN H. LANGE, a citizen of the United States, residing in New York city, New York, have invented a new and original Design for Hangings, of which the following is a specification, reference being had to the accompanying drawings, which form a part of the same.

The invention relates to a design to be imparted to wall-paper or other suitable material used as hangings to decorate walls; and it consists in the novel configuration and grouping of figures herein specifically shown and claimed.

In the accompanying drawings, Figure 1 is a face view of a part of a hanging, showing my new design applied thereto; and Fig. 2 is an enlarged transverse section of part of the same, taken on the line 2 2, Fig. 1.

My design is composed of a series of figures, circular in general outline and of various different sizes, so arranged as to conceal parts

one of another. These circular figures are each provided with several straight radial lines and curved lines joining the radial lines, 25 and some are provided with central dots. These curved lines are each circular in general outline and continuous, but are made up of several arcs of circles of smaller radius than the circle which represents the general 30 outline of the curved line, and each of these smaller arcs bridges the distance between two adjacent radial lines.

All of the parts of my design are formed in cameo or raised effect, as clearly shown in 35 Fig. 2.

What I claim, and desire to secure by Letters Patent, is—

The design for hangings, consisting of the design substantially as shown.

JOHN H. LANGE.
